UNITED STATES PATENT OFFICE.

ALBERT J. BATES, OF JOLIET, ILLINOIS, ASSIGNOR TO THE CONSOLIDATED STEEL AND WIRE COMPANY, OF CHICAGO, ILLINOIS.

WIRE-FENCE MACHINE.

SPECIFICATION forming part of Letters Patent No. 577,639, dated February 23, 1897.

Application filed September 4, 1896. Serial No. 604,857. (No model.)

To all whom it may concern:

Be it known that I, ALBERT J. BATES, a citizen of the United States of America, residing at Joliet, in the county of Will and State of Illinois, have invented certain new and useful Improvements in Wire-Fence Machines, of which the following is a full, clear, and exact description, such as will enable others skilled in the art to which it appertains to make and use the same.

The invention relates to the manufacture of woven-wire fences; and the general object in view is to make by machinery at one operation, in continuous lengths, a complete fencing or fence fabric, consisting of a plurality of longitudinal or strand wires having transverse stay-wires or braces spanning the spaces between the strand-wires and secured thereto, so as to connect them together and strengthen and support them.

This style of fencing is not new, and it has already been proposed to make the same by machinery at one continuous operation, but in doing so the transverse stay-wires corresponding to the spaces between the strand-wires have been divided into sets or groups, the individual wires of which correspond only to alternate spaces between the strand-wires, and these sets or groups have been fed in and secured to the strand-wires alternately, so that in the completed fencing the stay-wires are not continuous across the fabric, but are so located and arranged that at any given point of the fencing only alternate spaces between the strand-wires are crossed, the other spaces not being crossed by the stay-wires, and the longitudinal wires not being connected at all at that point.

It is the particular object of the present invention to provide a machine that will make this kind of fencing so that in the completed fabric all the longitudinal wires or as many as may be desired will be connected together by transverse stay-wires that are practically continuous and in line with one another, and this I accomplish by feeding all the stay-wires in simultaneously and in line with one another crosswise of the strand-wires and securing them to the strand-wires and to one another, thereby producing a fencing of superior strength, rigidity, and effectiveness and of

a greatly-improved appearance; and the invention consists in a machine organized and having its elements combined as hereinafter claimed and as contained in the machine herein illustrated and described as the best embodiment of the invention at this time known to me.

In the accompanying drawings, forming part of this specification, Figure 1 is a top plan of the machine. Fig. 2 is a side elevation of the same, looking at the machine from the right of Fig. 1. Fig. 3 is a side elevation of the same, looking at the machine from the lower side of Fig. 1. Fig. 4 is a horizontal section of the machine on line A A of Figs. 2 and 3, looking down. Fig. 5 is a detailed face view of the machine stay-wire coilers and a side view of the stay-wire-cutting-off mechanism, taken on line B B of Fig. 4, looking toward the right. Fig. 6 is a detailed view of the upper portion of said stay-wire coiling and cutting-off mechanism, showing the face of one cutter-bar and the side of the end portions of the coilers. Fig. 7 is a detailed view representing a section of the mechanism shown in Fig. 5 with the stay-wire cutters thereof brought to a position assumed when cutting off the stay-wire. Figs. 8 and 9 are detailed views representing different stages, in the process of operating the machine, of coiling the stay-wire ends about the strand-wires. Fig. 10 is a detailed view representing a section of the stationary cutter-bar shown at the right at Fig. 5, showing a stay-wire guide placed between two coilers. Fig. 11 is a cross-section of the same on line D D of Fig. 10. Fig. 12 is a detailed side view of the mechanism of the machine for operating the stay-wire coilers, the same being a portion of the mechanism shown in Fig. 2. Figs. 13 and 14 are detailed views representing sections of the mechanism shown in Fig. 12, showing by dotted lines the different relative positions of the rack and coiler-pinions. Fig. 15 is a cross-sectional view of said rack and one of said coiling-pinions, taken on line C C of Figs. 12 and 14, looking down, also showing keeper-plates at the sides of said rack. Fig. 16 is a side view of one of the stay-wire-coiling shafts and pinion of the machine, representing the coiling end of the same in section. Fig. 17 is a face view

of one pair of the stay-wire feed-rolls and gears thereof of the machine. Figs. 18 and 19 are detailed plan views of said feed-rolls. Figs. 20 and 21 represent sections of woven-wire fencing, the same being the product of the machine. Figs. 22 and 23 are detailed views of portions of said fencing, representing the manner in which the stay-wire ends are coiled about the strand-wires; and Fig. 24 is a detailed view of a portion of two fencing take-up rolls of the machine with a portion of the fencing between them.

Referring to the views, 1 denotes the bed-plate of the machine, arranged in a horizontal position upon any suitable foundation and secured thereto by foundation-bolts.

2 indicates the head-plate, supported in a horizontal position above the bed-plate upon posts 3 and 4, which rise from the bed-plate 20 and form bearings and supports for the wire feeding, coiling, guiding, and cutting mechanisms, as well as performing other functions, which will be hereinafter described.

5 denotes a post that is fixed to the bed and 25 head plates in line with the posts 3 and 4, and 6 is a column located between the posts 4 and 5 and forming a support for certain take-up rolls and tension devices, which will also be described later on.

30 Journaled on the upper side of the head-plate 2 in stand-bearings 7 and 8 is a shaft 9, having fixed thereon a bevel gear-wheel 10 and a ratchet-wheel 11, having four teeth. The shaft 9 has also splined upon it bevel gear-wheels 12 and 13, and loosely journaled upon the shaft is also a belt-pulley 14, which has fixed to its hub a spur-pinion 15, all as illustrated in Fig. 1. Likewise journaled upon the upper side of the head-plate in bearings 16 and 17 is a shaft 18, having a combined cam and crank wheel 19 at one end, a crank-disk 22 at the other end, a spur gear-wheel 20, and an eccentric 21. Also, journaled in a bearing 23 midway between the shafts 9 and 18 is an intermediate gear-pinion 24, meshing with the spur-pinion 15 and the gear 20 and operating to transmit movement from the former to the latter, so that a belt passing around the pulley 14 will drive the shaft 18 and its connected parts, and thereby, 45 through the agency of the arm 26, which is sleeved on the shaft 9 and carries a spring-pawl 27, arranged to engage the teeth of the ratchet-wheel 11, and the connecting-rod 25, which is arranged to connect the arm 26 with the crank-disk 22, to intermittently drive the shaft 9 and its connected parts.

Respectively stepped in boxes 28 and 29 on the bed-plate are shafts 30 and 31, which extend upwardly through the head-plate and have fixed on their upper ends, respectively, bevel-pinions 32 and 33, located and arranged so that gear 13 on shaft 9 may be set to mesh with the pinion 32, and gear 12 on the same shaft may be set to mesh with the pinion 33. The shaft 31 extends upwardly through a stand-bearing 34 above the pinion 33 and has

fixed to its upper end a horizontally-operating flanged belt-pulley 35.

Below the head-plate 2 the shaft 30 has 70 fixed thereon a spur-gear 36, and at a corresponding point the shaft 31 has a similar gear 37. These two gears are connected together through the intermediacy of an idler 38, which is studded to the under side of the head-plate, 75 so that when one of the shafts is driven the other will be likewise operated. The object of making the gears 12 and 13 splined and movable on the shaft 9 is that either one may be caused to mesh with its fellow gear on the 80 shafts 30 and 31, so that when the gear 12 meshes with the gear 33 the movement transmitted to the shafts 30 and 31 will be equal to that imparted to shaft 9, which, by reason of the ratchet-wheel 11 having four teeth and 85 operated one tooth at each actuation, will be a one-fourth turn, and when the gear 12 is moved out of mesh and the gear 13 is moved into mesh with the gear 32 the movement transmitted to the shafts 30 and 31 will, by 90 reason of the fact that the gear 32 has a pitch diameter one-half that of the gear 13, be a one-half turn at each actuation of shaft 9, this interchange of motion being for the purpose of varying the take-up movement of the 95 machine, so as to alter the distance apart of the stay-wires affixed to the strand-wires, as will be more fully explained later on.

Journaled in bearings in the posts 3 and 4 are a series or plurality of coiling-shafts 39, 100 arranged vertically one over another and located at graduated distances apart. These shafts are centrally and longitudinally bored to provide passage-ways therethrough for longitudinal strand-wires of the fencing, and 105 each is provided at the end where the wire enters with a pinion 43 and a wire-guide 40. At the opposite ends each of these coiling-shafts is provided with a tip 41, that is threaded into the end of the shaft and is provided 110 with two oppositely-located longitudinally-extending coiling-pins 42. The coiling-shafts are all placed so that their pinions 43 are in vertical line at the outer side of the post 3, and so that their coiling ends and the pins 42 115 protrude a short distance from the post 4 at the side thereof facing toward the center of the machine, as shown in Fig. 4.

Fulcrumed to the lower part of post 3 is a bell-crank lever 44, and to the upper part of 120 the post in vertical line with the lever 44 is fulcrumed a compound bell-crank lever 45. This lever has three arms, one downwardly extending, one upwardly extending, and one extending laterally parallel with the lever 44. 125 The upwardly and laterally extending arms are provided with wrist-rollers 46 and 47, respectively, that are arranged to operate against peripheral cams 48 and 49 on the cam-wheel 19, which cams are of such form as to 130 impart an intermittent oscillating movement to the compound lever 45 to lock it against movement during the intervals of its throw.

50 denotes a connecting-rod joining together

the laterally-extending arms of the levers 44 and 45, so that a like movement may be imparted to each.

51 denotes a bar which is pivotally studded to the downwardly-extending arms of the levers 44 and 45, and this bar has forwardly-extending side plates or keepers 52 and 53 fixed to it, the keepers 52 being made integral with a vertically-extending plate 54, as 10 shown. Slidably held between said keepers is a rack-bar 55, backed against the bar 51 and provided on its sides with longitudinal grooves 56, into which grooves extend inwardly-projecting ribs or flanges on the keepers 52 and 53 for the purpose of holding the rack against the bar 51 and at the same time allowing it to slide vertically along said bar.

Pivots connected to the back of the rack-bar by a box 58 is a lever 57, which lever is 20 pivoted at its opposite end to the upper end of an upright connecting-rod 59, which is pivoted at its lower end to a bracket 60, rising from the bed-plate 1.

Pivots connecting the central portion of 25 the lever 57 is a bar 61, which extends upwardly and is connected at its upper end to the crank 62 of the cam-wheel 19, so that movement is imparted from said crank to the lever 57, and a reciprocating motion is thereby 30 given to the rack-bar 55. In order to accommodate this movement of the box 58 on the rack-bar, the rack-supporting bar 51 is recessed, as shown at 151 in Fig. 12. The arrangement of the rack-bar is such that its 35 teeth face the pinions of the coiling-shafts 39, and when held at its back throw by the action of the levers 44 and 45 its teeth will be out of gear with said pinions, but when held at its forward throw its teeth will be in operative gear with said pinions. The object in 40 thus holding and operating the rack-bar is that at each upward movement thereof it will be in mesh with and rotate the coiler-pinions and at each downward movement it will be 45 held out of mesh with said pinions, so as not to rotate them. In this way the coilers are rotated only in one direction, and for the purpose of locking the coiler-pinions against rotation when the rack is out of mesh there- 50 with the plate 54, which is held close to the ends of the coiling-shafts and pinions, is provided with a series of inwardly-extending pins 63, one pin being located relatively to each pinion on the opposite side from the rack and 55 so stationed that when the rack is in mesh with the pinions it will be out of engagement and when the rack is out of mesh it will engage the pinion and prevent the same from being turned out of proper position for the 60 remeshing of the rack therewith, all as clearly shown in Figs. 13 and 14.

As a means of providing ways through plate 54 for the entrance of the strand-wires to the coiling-shafts 39, as well as to permit the plate 65 to move laterally with respect to the pinions 43, it is made with a series of slots 64, extending laterally, as shown in Figs. 13 and 14.

Journalized to the post 3 and the head-plate 2 at one side of the coiler-pinions 43 is a vertical shaft 67, having fixed on its upper end 70 a bevel-pinion 68, arranged to gear with and be intermittently operated by the gear 10 on the end of the shaft 9. Fixed on this shaft 67 at graduated distances apart along its length corresponding to the positions of the 75 coiling-shafts is a plurality of feed-rolls 69, and journaled in bearings at the free ends of spring-arms 70, which are secured to and supported by an upright bar 71, extending parallel with said shaft, are corresponding feed-rolls 72, arranged to operate one with each roll 69 and so proportioned that each is twice the diameter of its fellow roll 69. Each pair of these feed-rolls 69 and 72 is provided with 80 a pair of intermeshing spur-gears 73 and 74 85 for the purpose of imparting a positive rotation to the rolls 72 from the rolls 69. There is one pair of spring-arms 70 for each of the rolls 72, one arm being below and the other above the roller, and secured to the upright 90 bar 71 in proximity to each pair of these arms is a bracket 75, which pivotally supports a cam-faced lever 76, these levers being for the purpose of being operated to bring their cam-faces against the spring-arm 70 with sufficient 95 pressure to force and hold the feed-roll 72 in yielding contact with the wire being fed into the machine between the rolls and to be operated to release said spring-arms from such force, so that they will hold the rolls 72 out 100 of contact with the wire at such times as it may be necessary or desirable to stop the in-feeding of the wire during the operation of the machine.

Fixed in suitable bearings upon posts 3 are 105 a series or plurality of stay-wire guide-tubes 77, one tube being arranged to receive the wire fed forward by each pair of rolls 69 and 72. These tubes are curved laterally toward the coiling-shafts and extend upwardly and 110 inwardly each to a point a little below the coiling end of one of the coiling-shafts 39, so that the wires fed through said tubes pass upwardly across the face of the coilers between the strand-wires passing through the 115 latter and the coiling-pins 42 in a curved direction, as represented in Figs. 5 and 6.

The post 4, in addition to providing fixed bearings for the coiling ends of the coiling-shafts 39, constitutes the stationary cutter-bar of the machine and has secured to its side a plurality of duplicate cutters 78, which are held to their seats by means of cap-plates 79 and are made adjustable by set-screws 80. These cutters are arranged in relation to the 120 coilers and so timed in their operation as to cut the stay-wires when a sufficient length has been fed through the guide-tubes to span the spaces between the coilers and the longitudinal strand-wires passing through them. 125 There is one cutter stationed a little below each coiler except the upper one, and each operates in conjunction with a movable cutter, which I will now describe.

Referring to Sheet 5 of the drawings, 81 denotes a bar extending parallel with the bar 4 and movable toward and from the latter by being mounted at its opposite ends on the 5 wrists 82 of eccentric-levers 83 and 84, that are fulcrumed on fixed pins 85 and 86. 87 is a rod arranged to connect the levers 83 and 84 together, so that their movement will be joint, and this rod and levers are operated 10 through the intermediacy of the arm 88 and a strap around the eccentric 21. This bar 81 constitutes the movable cutter-bar of the machine, and seated in its side in substantially the same manner that the stationary cutters 15 are seated in the bar 4 are a plurality of cutters 89, so arranged that as the bar 81 moves toward the fixed cutter-bar the cutters 89 will coöperate with the fixed cutters 78 to cut the wire, and the movement of these cutters, 20 owing to the operating connections above described, is on a downward curve, as shown in dotted lines in Fig. 9.

Attached to the post 4 in fixed relation to the coilers are guides 90, said guides occupying 25 places between the coilers except when the coilers are in such close proximity as to permit the guides to be dispensed with. These guides are made with open-faced grooves 91, preferably of a form corresponding 30 with the curvature of the stay-wires, and are provided with yielding face-plates 92, connected therewith with spring-hinges, as shown in Fig. 10, and operating to normally close the grooves 91 and hold the wires in the 35 guides, but permitting the wires to be released therefrom after the coilers have wrapped their ends around the strand-wires. Confined guideways are thus formed for the infeeding of the stay-wires, so that they may 40 not be deflected from their proper course and so that they will be held between the coilers while their ends are being coiled around the strand-wires. After the stay-wires have been attached to the strand-wires the forward 45 feeding of the fencing through the machine causes them to bear against the yielding face-plates and force them open to release the wires, after which the spring-hinges of the plates cause them to close ready for a succeeding 50 feed of the stay-wires. In Fig. 5 these guides 90 are omitted to avoid confusion.

Fixed upon the shaft 30 is a plurality of take-up rolls corresponding in number to the number of the strand-wires and arranged at 55 graduated distances apart in accordance with the arrangement of the coilers. Each of these rollers is provided with peripheral notches or recesses 94. Fixed upon the shaft 31 is a like series of rolls 95, arranged in the same order, 60 and supported in bearings in spring-arms 96, which are attached to the column 6 by means of brackets 97, are a plurality of tension-rollers 99, and these tension-rollers are arranged in the same order as the take-up rolls 93 and 65 95, so that the take-up mechanism for each strand-wire comprises a series of three rolls—viz., 93, 99, and 95. Each of the tension-

rollers 99 is adjusted to bear against or relieved from its fellow rolls 93 and 95 by means of a cam-faced lever 98 in like manner as described of the levers 76. 70

100 represents the vertically-arranged winding-drum for reeling the completed fencing. It consists of two parts, preferably of wood, nearly semicircular in cross-section, and both 75 seated at their lower ends in recesses of a stand 101, being locked therein by means of a cross-key 102, passing through the parts of the drum and through a central vertical web of the stand, said stand being stepped in bearings on the bed-plate in box 103. The upper ends of the sections of the drum are placed in a head-piece 105, which is similar in construction to the stand 101 and is fitted on a short shaft journaled in a box 106, attached 85 to one end of the laterally-extending arm 107 of the head-plate. A key 104, similar to the key 102 in the stand 101, locks the upper end of the sectional drum in the head-piece. 80

Sleeved on the upper end of the shaft 108 90 is a belt-pulley 111, similar to the pulley 35 on the shaft 31. Attached to this pulley is a spring-pawl 109, and fixed on the upper end of the shaft 108 of the drum is a ratchet-wheel 110, arranged so that its teeth will be engaged 95 by the pawl. A belt 112 travels around the pulleys 111 and 35 and transmits motion from the pulley 35 to the drum mechanism for reeling the completed fencing into rolls as it is delivered from the take-up mechanism. The 100 pawl-and-ratchet connection between the pulley 111 and the drum is for the purpose of adapting the drum to rotate forwardly independent of its driving mechanism, so as to take up the slack when starting the winding 105 of a roll thereon.

The strand-wires employed in the manufacture of the fencing are represented at 113 and are taken directly from the coils or spools on which the wire is received from the wire-making 110 machine. These wires are passed one through each coiler 39, thence to and between the faces of the take-up rolls 93 99 95, and thence about the rolls 95 to and around the winding-drum 100. During the operation of 115 the machine these wires are intermittently pulled forward through the coilers by the take-up rolls and delivered to the winding-drum.

The stay-wires are indicated at 114 and are also taken from the usual coils or spools and 120 placed one between each pair of feed-rolls 69 and 72, which rolls, by reason of the intermittent movement that is imparted to them, feed the wires forwardly with an intermittent motion, the relative pitch diameters of the 125 gears 10 on the main shaft 9 and 68 on the shaft of the rolls 69 being such that at each actuation of the shaft 9 the rolls make one complete rotation, and the diameters of said rolls are such that they feed forward a sufficient length of the stay-wires for spanning the spaces between the strand-wires and for 130 making the coils about the same.

In feeding in the stay-wires their coil cur-

vature is maintained and utilized, so that as the wires pass from the tubes 77, which are vertically in line with the end of the coilers, they pass up beyond the nose of the stationary cutters 78 between one coiling-pin 42 and the strand-wire, thence on an inward or side-bowing course over the cutter 78 next above, and thence between the coiling-pin 42 and the strand-wire of the coiler next above and 5 in a position on the opposite side of the strand-wire from the one formerly passed. The several stay-wires thus fed forward are presented with their body portions bowed off from the post or stationary cutter-bar 4 and with their 10 end portions crossed at the strand-wires, their ends also inclining toward and against the tips of the coilers and within the limit of the pins 42, so that the rotation of the coilers will cause the pins to engage the ends and jointly 15 intercoil them with each other and around the strand-wires. This joint action of the coilers causes all the meeting ends of the 20 lengths of stay-wires which span the spaces between the strand-wires to be intercoiled and 25 form a practically continuous stay-wire across the width of the fencing. The bowed position of the body portions of the stay-wires during the coiling of their ends brings them sufficiently off from the coilers so as not to 30 be engaged by the pins.

The infeeding of the stay-wires takes place at the time the pawl-and-ratchet mechanism 11 25 26 27 actuates the shaft 9, and at this time the strand-wires are also pulled forward 35 with their attached stay-wires, the fencing being then wound on the drum 100, and during the one-half movement of the machine while the shaft 9 is idle the coiling-shafts are rotated to coil the ends of the stay-wires 40 around the strand-wires.

In the construction of the feed-rolls 69 and 72 the latter are made twice the diameter of the former, and when all the rolls 72 are made with full peripheries, as shown in Fig. 18, 45 they are in constant contact with the stay-wires, and at each revolution of the roll 69 they make one-half a revolution, resulting in the production of the fencing shown in Fig. 20. For the purpose of producing the fencing shown in Fig. 21, with alternate stay-wires shorter or connecting only a limited number 50 of the strand-wires, the rolls 72 or such of them as represent the blank spaces in the fencing shown in the drawings are cut away at one-half of their peripheries, as shown in Fig. 19, so that at each alternate half-rotation they 55 will be liberated from pressure against the stay-wires and not make a feed, but at the succeeding alternate half-rotations their full 60 peripheral portions will engage and feed forward the stay-wires.

In drawing the strand-wires through the coiling mechanism by the take-up rolls they are pinched by the rolls with sufficient pressure 65 to feed them through the machine and on toward the winding-drum, and the rolls are so located that the coils of the stay-

wires about the strand-wires register with the peripheral notches or recesses 94 of the rolls 93 and 95, so as not to crush the coils, 70 and for the further purpose of making short bends or crimps in each strand-wire at the ends of the stay-wire coils, which bends prevent the displacement of the stay-wire coils and incidentally afford elasticity to the finished fencing, so as to adapt it to expand and contract under atmospheric influences. The manner of this crimping will be understood from Fig. 24, where the plain surface of the roll 99 causes the coils of the stay-wires to 80 pass into the recesses 94, and the shoulders of the roll 93 adjoining the recesses bend the strand-wires, as there represented.

When the take-up rolls are given a one-fourth rotation at each actuation of the machine, the advance of the strand-wires is such that the stay-wires will be placed sufficiently close together for their coiled ends to register with each peripheral notch 94, but when a one-half rotation is given the rolls for each 90 actuation of the machine only every other notch 94 will register with the stay-wire coils.

The construction and operation of the machine being as above described, it will be noted that fencing of various heights or 95 widths may be made by omitting one or more of the strand-wires 113 and the corresponding stay-wires 114, also that the stay-wires may all be made continuous across the fencing, or alternate ones only may go clear 100 across, the others extending so far across as may be desired. It will also be noted that by graduating the distances apart of the coiling-shafts the strand-wires may be uniformly spaced apart or be closer together at 105 the lower part of the fencing.

In the following claims I do not wish to be understood as limiting myself as to the details of construction of the individual elements going to make up the several parts or 110 combinations of the machine herein illustrated and described, as I regard the invention as of a character to admit of variations of these details within considerable limits without departing from its spirit or scope. 115 For example, the details of the coilers, the cutters, the feeding and take-up mechanisms, and other parts may be differently constructed so long as the organization, relative arrangement, and combinations are preserved, and the framing of the machine, the gearing, &c., are features that admit of a 120 wide range of modification within the skill of the designer and machine-constructor.

Having thus described the invention, what 125 I claim, and desire to secure, is—

1. In a wire-fence machine, the combination of mechanism for intermittently feeding a plurality of longitudinal strand-wires, mechanism for intermittently feeding a plurality 130 of stay-wires simultaneously and transversely of the strand-wires, mechanism for cutting off suitable lengths of the stay-wires to span the spaces between the strand-wires, and mech-

- anism for simultaneously coiling the adjacent ends of the lengths of the stay-wires around the strand-wires.
2. In a wire-fence machine, the combination 5 of mechanism for intermittently feeding a plurality of longitudinal strand-wires, mechanism for intermittently feeding a plurality of stay-wires simultaneously and transversely of the strand-wires, mechanism for cutting off 10 suitable lengths of the stay-wires to span the spaces between the strand-wires, and mechanism for intercoiling the adjacent ends of the lengths of the stay-wires around the strand-wires.
3. In a wire-fence machine, the combination 15 of mechanism for intermittently feeding a plurality of longitudinal strand-wires, mechanism for intermittently feeding a plurality of stay-wires simultaneously and in line with 20 one another transversely of the strand-wires, mechanism for cutting off suitable lengths of the stay-wires to span the spaces between the strand-wires, and mechanism for intercoiling the adjacent ends of the lengths of the stay-wires around the strand-wires.
4. In a wire-fence machine, the combination 25 of mechanism for intermittently feeding a plurality of longitudinal strand-wires, mechanism for intermittently feeding a plurality of stay-wires simultaneously and in line with 30 one another transversely of the strand-wires, mechanism for cutting off suitable lengths of the stay-wires to span the spaces between the strand-wires, mechanism for coiling the outer 35 ends of the outermost lengths of the stay-wires around the border strand-wires, and mechanism for intercoiling the adjacent ends of the lengths of the stay-wires around the intermediate strand-wires.
5. In a wire-fence machine, the combination 40 of mechanism for intermittently feeding a plurality of longitudinal strand-wires, mechanism for intermittently feeding a plurality of stay-wires simultaneously and transversely 45 of the strand-wires, mechanism for cutting off suitable lengths of the stay-wires to span the spaces between the strand-wires, mechanism for simultaneously coiling adjacent ends of the lengths of stay-wires around the strand-wires, and mechanism for crimping the 50 strand-wires at the junction of the stay-wires to more firmly secure the latter.
6. In a wire-fence machine, the combination 55 of mechanism for intermittently feeding a plurality of longitudinal strand-wires, mechanism for intermittently feeding a plurality of stay-wires simultaneously and transversely of the strand-wires, mechanism for cutting off suitable lengths of the stay-wires to span the 60 spaces between the strand-wires, mechanism for intercoiling the adjacent ends of the lengths of the stay-wires around the strand-wires, and mechanism for taking up the fencing as it is formed.
7. In a wire-fence machine, the combination 65 of a plurality of coilers through which longitudinal strand-wires are fed, a plurality of 70 guides through which stay-wires are fed transversely to the coilers, mechanism for cutting off suitable lengths of the stay-wires to span the spaces between the strand-wires, and mechanism for holding the stay-wires intermediately of the coilers while their ends are being coiled around the strand-wires.
8. In a wire-fence machine, the combination 75 of a plurality of coilers through which longitudinal strand-wires are fed, a plurality of guides through which stay-wires are fed transversely to the coilers, mechanism for cutting off suitable lengths of the stay-wires to span 80 the spaces between the strand-wires, said guides being adapted to hold the cut lengths of the stay-wires intermediately of the coilers while their ends are being coiled around the strand-wires, and to yield so as to release the 85 stay-wires after the coiling operation.
9. In a wire-fence machine, the combination 90 of a plurality of coilers through which longitudinal strand-wires are fed, a plurality of guides through which transverse stay-wires 95 are fed to the coilers, mechanism for feeding in the stay-wires transversely of the strand-wires, and mechanism for cutting off suitable lengths of the stay-wires to span the spaces between the strand-wires, said feeding and cutting mechanisms being arranged and adapted 100 to feed the stay-wires in and cut them off with the ends of adjacent lengths overlapping at the coilers.
10. In a wire-fence machine, the combination 105 of a plurality of coilers through which longitudinal strand-wires are fed, mechanism for feeding a plurality of stay-wires transversely of the strand-wires, mechanism for cutting off suitable lengths of the stay-wires 110 to span the spaces between the strand-wires, and mechanism for rotating the coilers in one direction only to coil the ends of the stay-wires around the strand-wires.
11. In a wire-fence machine, the combination 115 of a plurality of coilers through which longitudinal strand-wires are fed, mechanism for feeding stay-wires to the coilers transversely of the strand-wires, mechanism for cutting the stay-wires, mechanism for intermittently rotating the coilers in one direction 120 only, and mechanism for locking the coilers against rotation during the intermission of the coiler-rotating mechanism.
12. In a wire-fence machine, the combination 125 of a plurality of coilers through which longitudinal strand-wires are fed, mechanism for feeding stay-wires to the coilers transversely of the strand-wires, mechanism for cutting the stay-wires, a gear-rack for rotating the coilers in one direction only, and mechanism for throwing said rack into and 130 out of engagement with the coilers.
13. In a wire-fence machine, the combination 135 of a plurality of coilers through which longitudinal strand-wires are fed, mechanism for feeding stay-wires to the coilers transversely of the strand-wires, a rack-bar for intermittently rotating the coilers in one direc-

tion only, mechanism for throwing said rack into and out of engagement with the coilers, and means for locking and holding the coilers while the rack is out of engagement there-
5 with so as to prevent rotation and insure the reengagement of the rack.

14. In a wire-fence machine, the combination of a plurality of coilers arranged in line with one another, a gear-rack for rotating said coilers, said rack being supported in parallel relation with the line of coilers by pivoted levers, and mechanism for swinging the levers to throw the rack into and out of engagement with the coilers.

15. In a wire-fence machine, the combination of a plurality of coilers arranged in line with one another, a gear-rack for rotating said coilers, a rack-supporting bar, pivoted levers carrying said bar, a rod connecting said levers, mechanism for swinging the levers to throw the bar and its rack toward and from the coilers, and mechanism for reciprocating the rack.

16. In a wire-fence machine, the combination of a plurality of coilers arranged in line with one another, the gear-rack 55 supported in parallel relation with the line of coilers on pivoted levers 44, 45, the rod 50 connecting said levers to move together, and the cam-
30 wheel 19 upon which the rollers 46, 47 of the lever 45 work.

17. In a wire-fence machine, the combination of a plurality of coilers arranged in line with one another, the gear-rack 55 supported in parallel relation with the line of coilers on pivoted levers 44, 45, the rod 50 connecting said levers to move together, the cam-wheel 19 upon which the rollers 46, 47 of the lever 45 work, the lever 57 pivotally connected to the rack-bar and to the connecting-rod 59, and the rod 61 connecting the lever 57 to the crank 62 of the cam-wheel.

18. In a wire-fence machine, the combination of a plurality of coilers arranged in line with one another, a reciprocating rack-bar in parallel relation with said line of coilers and adapted to be thrown laterally into and out of engagement therewith, a keeper-plate movable laterally with the rack-bar, and pins 63
50 on the plate at the opposite side of the coiler-pinnions from the bar.

19. In a wire-fence machine, the combination of a plurality of coilers through which longitudinal strand-wires are fed, guide-tubes
55 corresponding to the coilers for feeding transverse stay-wires thereto, and guides located between the coilers for directing the stay-wires from one coiler across the intervening space to the next adjacent coiler.

60. 20. In a wire-fence machine, the combination of a plurality of coilers through which longitudinal strand-wires are fed, guides extending between the coilers for directing the stay-wires from one coiler across the intervening space to the adjacent coiler, and cutters for cutting the stay-wires after they have been projected through the guides, said guides

being adapted to hold the stay-wires during the operation of the coilers and to release them after the coiling is completed.

21. In a wire-fence machine, the combination of a plurality of coilers through which longitudinal strand-wires are fed, co-operating rolls for feeding stay-wires through the coilers transversely of the strand-wires, and mechanism for throwing individual feed-rolls out of action so as to interrupt the feeding in of individual stay-wires.

22. In a wire-fence machine, the combination of a plurality of coilers through which longitudinal strand-wires are fed, the shaft
67 carrying feed-rolls 69, one for each coiler, the co-operating feed-rolls 72 mounted in spring-arms and geared to the rolls 69, and the cam-faced levers 76 for throwing the rolls 85
72 in operative connection with the rolls 69.

23. In a wire-fence machine, the combination of the driven feed-rolls 69, the co-operating rolls 72 geared to the rolls 69, the spring-
90 arms 70 in which the rolls 72 are mounted, and the cam-faced levers 76 for throwing the rolls 72 in operative connection with the rolls 69.

24. In a wire-fence machine, a stay-wire-feeding mechanism comprising driven feed-rolls, and co-operating feed-rolls geared there-
95 to, the co-operating rolls having a diameter twice that of the driven rolls, and having one-half of their peripheries cut away.

25. In a wire-fence machine, the combination of strand-wire-feeding mechanism, stay-wire-feeding mechanism, and stay-wire cutting and coiling mechanism, of mechanism for crimping the strand-wires at the junction of the stay-wires, said mechanism consisting of rolls between which the completed fencing 105 passes, one of said rolls having a plain surface and the other being provided with notches or recesses into which the coils of the stay-wires pass.

26. In a wire-fence machine, the combination of strand-wire-feeding mechanism, stay-wire-feeding mechanism, mechanism for cutting the stay-wires and coiling them around the strand-wires, the tension-roll 99 having a plain periphery, and the take-up roll 93 having notches or recesses 94 in its periphery, the surfaces of the rollers 99 and 93 being in such proximity that the strand-wires are crimped at the junction of the stay-wire coils as the coils pass into the recesses 94.

27. In a wire-fence machine, the combination of a plurality of coilers, a stationary cutter-bar carrying a plurality of cutters corresponding to the coilers, a movable cutter-bar carrying a plurality of cutters corresponding 125 to and co-operating with the fixed cutters, and mechanism for moving the movable cutter-bar toward and from the stationary bar so that all the cutters will operate simultaneously.

28. In a wire-fence machine, the combination of a plurality of coilers, a stationary cutter-bar carrying a plurality of cutters corresponding to the coilers, and a movable cutter-

bar carrying a plurality of cutters corresponding to and coöperating with the fixed cutters, said movable bar being mounted on eccentric-wrists 82 of a pair of connected levers 83, 84 connected together by a rod 87, and means for operating the levers.

29. In a wire-fence machine, the combination of take-up rolls for taking up the completed fencing, tension-rolls coöperating with 10 said take-up rolls, spring-arms in which the tension-rolls are mounted, and cam-faced levers for throwing the tension-rolls in operative connection with the take-up rolls.

30. In a wire-fence machine, the combination of strand-wire-feeding mechanism, stay-wire-feeding mechanism, mechanism for cutting the stay-wires and coiling them around the strand-wires, mechanism for taking up the completed fencing, and differential gearing for driving the take-up mechanism, whereby the distance apart of the stay-wires may be varied.

31. In a wire-fence machine, the combination of the shafts 30, 31 of the take-up mechanism, said shafts being intergeared by the gears 36 and 37, respectively, and the idler 38, of the drive-shaft 9 having the adjustable gears 12 and 13 adapted to mesh with the gears 32 and 33 on the shafts 30 and 31 respectively.

32. In a wire-fence machine, the combination of a winding-drum, a ratchet-wheel fixed on the shaft of the drum, a driving-wheel loosely journaled on said shaft, and a pawl 35 carried by the driving-wheel and engaging the ratchet-wheel.

33. In a wire-fence machine, the combination of a longitudinally-sectional winding-drum, a driven head-piece in which one end 40 of each of the drum-sections are fitted, a rotatable stand in which the other ends of the drum-sections are fitted, and means for releasably securing said sections together and to the head and stand.

45 34. In a wire-fence machine, the combination of the driven head-piece 105, the rotatable stand 101, the longitudinally-sectional

winding-drum composed of the parts 100, 100, and the detachable fastening-keys 102, 104.

35. In a wire-fence machine, the combination of a plurality of coilers through which longitudinal strand-wires are fed, a plurality of guides through which stay-wires are fed to the coilers transversely of the strand-wires, mechanism for feeding the stay-wires through 55 the guides, and mechanism for cutting off suitable lengths of the stay-wires to span the spaces between the strand-wires, said guides being curved so as to present the ends of the stay-wires at an angle to the face of the coilers 60 in order that the body portion of the wires may not interfere with the action of the coiling-pins.

36. In a wire-fence machine, the combination of a plurality of coilers arranged in vertical line one over another, a plurality of similarly-arranged guides and feed-rolls for feeding stay-wires to the coilers, take-up rolls for taking the fencing from the coilers, and a winding-drum for reeling the completed fencing, said take-up rolls and winding-drum being located and arranged in parallel relation to the line of coilers and stay-wire feed-rolls.

37. In a wire-fence machine, the combination of bed and head plates, suitably connected by vertical standards, a plurality of coilers arranged in vertical line one over another, a vertically-reciprocating rack-bar in parallel relation with the line of coilers, a plurality of vertically-arranged guides and 80 feed-rolls for directing and feeding stay-wires to the coilers, take-up and tension rolls for taking the fencing from the coilers, and a winding-drum for reeling the completed fencing, said take-up rolls and winding-drum being located and arranged vertically in parallel relation to the line of coilers.

In testimony that I claim the above I hereunto affix my signature in the presence of two witnesses.

ALBERT J. BATES.
